(57) **CLAIM**

The ornamental design for a two-in-one cosmetic container, as shown and described.

DESCRIPTION

FIG. 1 is a front perspective view of the two-in-one cosmetic container.

FIG. 2 is a front elevation view of the two-in-one cosmetic container.

FIG. 3 is a rear elevation view of the two-in-one cosmetic container.

FIG. 4 is a right side view of the two-in-one cosmetic container.

FIG. 5 is a left side view of the two-in-one cosmetic container.

FIG. 6 is a top view of the two-in-one cosmetic container.

FIG. 7 is a bottom view of the two-in-one cosmetic container.

FIG. 8 is an alternative perspective view of the two-in-one cosmetic container shown in an open configuration.

FIG. 9 is an alternative perspective view of the two-in-one cosmetic container in an exploded configuration; and,

FIG. 10 is a front perspective view of a second embodiment of the two-in-one cosmetic container with a top container having a pattern different from a bottom container.

The appearance of any portion of the two-in-one cosmetic container shown with dashed lines forms no part of the claimed design.

1 Claim, 10 Drawing Sheets
